A convertible light confining device for use in lamp housings of photographic projection printers resembles a hollow truncated pyramid through which the light passes in a direction from the top plane toward the base plate or vice versa. The sides of the truncated pyramid have rectangular or trapezoidal central portions which are pivotable inwardly about axes located in the top plane to form a second light duct of constant cross-sectional area or a second light duct which

resembles a hollow truncated pyramid having a base plane coinciding with the top plane of the first truncated pyramid and a top plane which is smaller than but coplanar with the base plate of the first pyramid.

Fig.4

LAMP HOUSING FOR USE IN PHOTOGRAPHIC ENLARGERS OR THE LIKE

BACKGROUND OF THE INVENTION

The present invention relates to light confining devices in general, and more particularly to improvements in light ducts or light pipes which can be used in lamp housings of photographic projection printers or the like.

In a photographic projection printer which is used as an enlarger, the image of an original must be projected onto a layer of photosensitive material to make a print. A versatile enlarger should be capable of making enlargements of different sizes, i.e., to make larger or smaller prints from a negative. In presently known enlargers, the light is not utilized with a satisfactory degree of economy. This is due to the fact that, in such enlargers, only the area of the largest negative is illuminated uniformly and with a maximum degree of efficiency; however, if an enlargement is to be made from a smaller negative, the superfluous illuminated area is covered with opaque masks which results in considerable losses of light energy and prolongs (relatively speaking) the projection time. It is also known to use in such projection printers sets of interchangeable condenser lenses or to furnish the printer with interchangeable light ducts. Interchangeable lenses or ducts reduce light losses but their mounting in or removal from the projection printer takes up much time with attendant losses in output.

SUMMARY OF THE INVENTION

An object of the invention is to provide a photographic projection printer with a novel and improved light confining device which can be used in the lamp housing as a light duct and can be converted to properly illuminate larger or smaller areas of photosensitive material with minimal losses in time and without necessitating even partial dismantling of the lamp housing.

Another object of the invention is to provide a convertible light confining device which can be used for making enlargements from originals of different sizes and is sufficiently simple to be entrustable to semi-skilled or unskilled persons.

A further object of the invention is to provide a convertible light confining device which can be installed in existing projection printers as a superior substitute for presently employed sets of light ducts.

An additional object of the invention is to provide a convertible light confining device which does not occupy more space than a conventional light duct.

The invention is embodied in a lamp housing for use in photographic projection printers or the like, and more particularly in a light confining and guiding device which forms part of the lamp housing and comprises a plurality of walls movable between first and second positions. When the walls are moved to the first positions, the light confining device constitutes a first light duct in the form of a hollow truncated pyramid with spaced apart top and base planes and sides which confine light that enters the first duct by passing across one of the planes and issues from the first duct by passing across the other plane. When the walls are moved to the second positions, the light confining device constitutes a second light duct which may form a second hollow truncated pyramid or a hollow shaft of constant or nearly constant cross section from end to end.

In accordance with a presently preferred embodiment, the walls constitute the central portions of the sides of the first light duct and are pivotable about axes located in the top plane of the first duct. One of the light ducts is preferably located within the confines of the other light duct.

The novel features which are considered as characteristic of the invention are set forth in particular in the appended claims. The improved lamp housing itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a fragmentary schematic elevational view of a photographic projection printer having a lamp housing with a light duct which embodies the invention;

FIG. 2 is a diagrammatic perspective view of a light duct which is constructed and assembled in accordance with a first embodiment of the invention;

FIG. 3 is a perspective view of a modified light duct;

FIG. 4 is a fragmentary vertical sectional view of the light duct shown in FIG. 3; and

FIG. 5 is a fragmentary vertical sectional view of the light duct shown in FIG. 2.

DESCRIPTION OF THE PREFERRED EMBODIMENTS

Referring first to FIG. 1, there is shown a portion of a photographic projection color printer which is used as an enlarger and embodies a lamp housing including the improved convertible light confining and guiding device. The light issuing from a source 1 is reflected by a reflector 2 so that it passes through a light confining device 4. The top part of the device 4 is adjacent to a unit 3 which includes a diffusing screen, means for changing the color of light and a shutter. The lower end of the device 4 is adjacent to a further diffusing screen 5. The parts 2-5 together constitute a lamp housing for the light source 1. The light issuing from the device 4 and passing through the diffusing screen 5 thereupon passes through an original 6 and is focussed by an objective lens system 7 so that a portion 6a of the original is imaged onto a section 8a of photosensitive print material 8. The lens system 7 preferably includes a lens of variable focal length. Save for the improved device 4, the just described enlarger is of conventional design and is of the type which is used extensively for automatic making of prints from originals, e.g., from successive frames of an exposed and developed photographic roll film. Enlargers employing light ducts in place of conventional condenser lenses are preferred for the making of color prints because the light duct serves as a means for mixing the colors of printing light in accordance with the setting of the color changing means (such as filters) forming part of the unit 3. The means for transporting the originals 6 and the photosensitive material 8, the control means for the unit 3 and other conventional parts of the enlarger are not shown in FIG. 1.

The construction of the improved light confining device 4 is shown schematically in FIG. 2. The diffusing screen 5 and the unit 3 are omitted in FIG. 2 for the sake of clarity. Basically, the light confining device 4

comprises a light duct in the form of a hollow truncated pyramid which, in the embodiment of FIG. 2, is a regular quadrangular truncated pyramid with a base plane 42, a top plane 40 which is assumed to be parallel to the base plane 42, and four trapezoidal sides. The light enters by passing across the top plane 40 and issues by passing across the base plane 42 which latter is overlapped by the diffusing screen 5.

In accordance with a feature of the invention, each of the four trapezoidal sides comprises a pivotable trapezoidal central portion or wall 41a, 41b, 41c, 41d and two triangular corner portions 42a-42a', 42b-42b', 42c-42c', 42d-42d'. When the central portions or walls 41a-41d are pivoted from register with the respective corner portions, they constitute a second light duct in the form of a second hollow truncated pyramid having a base plane coinciding with the top plane 40 of the light duct with the base plane 42 and four sides (41a-41d). The top plane 41 of the smaller second truncated pyramid is coplanar with or adjacent to the base plane 42. The edge portions 40a, 40b, 40c, 40d define pivot axes which are located in the plane 40 and about which the walls 41a-41d are pivotable from alignment with the respective corner portions to the positions shown by solid lines in which they constitute the sides of the smaller truncated pyramid. Thus, by the simple expedient of pivoting the walls 41a-41d about the edges 40a-40d, one can convert the relatively large light duct with a base plane 42 into a relatively small light duct with a base plane 40.

The details of means for moving slightly modified central portions or walls 41a'-41d' between the solid-line second positions and the first positions of alignment with the respective corner portions 42a-42a', 42b-42b', 42c-42c', 42d-42d' are illustrated in FIGS. 3 and 4. The walls 41a'-41d' are rectangular so that they may constitute a parallelepiped second light duct with a base plane 40' which is of the same size as the top plane 41'. The walls 41a'-41d' are respectively biased by helical springs 43a, 43b, 43c, 43d which tend to maintain them in alignment with the respective corner portions whereby the walls form part of the sides of a truncated pyramid having a base plane 42' and a top plane 40'. Each helical spring is attached to that part of the respective wall which is remote from the corresponding edge portion 40a', 40b', 40c', 40d' and the springs are further secured to fixed retainers 44a, 44b, 44c, 44d on the rigid frame of the enlarger. The frame is further rigid with the corner portions 42a-42d'. The walls 41a', 41b', 41c', 41d' are further provided with arcuate followers 45a, 45b, 45c, 45d which are adjacent to the respective edge portions 40a'-40d' and abut against the underside of a ring-shaped actuating member 46 which is movable in and counter to the direction indicated by an arrow 47. When the actuating member 46 is moved upwardly, as viewed in FIG. 3, the springs 43a-43d are free to contract and to return the walls 41a'-41d' to their first or outer end positions.

As shown in FIG. 4, the wall 41c' is substantially vertical when it forms one side of the smaller light duct and makes an oblique angle with the base plane 42' when it forms part of one side of the larger duct. Therefore, the larger duct must be provided with additional portions or sills 48a, 48b, 48c, 48d which are respectively aligned with and are adjacent to the lower edges of the walls 41a'-41d' when the walls form part of the larger duct. Such sills are desirable whenever the angle

beta between the base plane 42' and a wall 41a', 41b', 41c' or 41d' in the inner end position of such wall is larger than the angle alpha between the base plane 42' and a wall in the outer end position of such wall.

Referring to FIG. 5, there is shown a wall 41a which is assumed to form part of the light confining device of FIG. 2. The angle alpha equals the angle beta and, therefore, the sills 48a-48d of FIG. 3 can be dispensed with. However, and in order to avoid that the wall 41a extend downwardly and beyond the base plane 42 (i.e., that the wall 41a need not move the diffusing screen 5 of FIG. 1 downwardly) while the wall 41a pivots between its two end positions, the wall 41a is coupled to the remaining parts of the light confining device 4 by a pin-and slot connection 40aa to thus insure that the wall can move up or down during pivotal movement between the positions shown in FIG. 5.

The length of a side of the smaller duct should not exceed the length of a side of the larger duct because, otherwise, sills must be provided in the larger duct to be aligned with the pivotable walls in the inner end positions of the walls. Such sills would interfere with the travel of light through the larger duct. Therefore, the angle alpha is smaller than or at most equals the angle beta, i.e., the inclination of the sides of the smaller duct relative to the base plane of the larger duct should not exceed the inclination of the sides of the larger duct.

It is to be noted that the light confining devices are normally longer than those shown in FIGS. 2 and 3. The ratio of the maximum transverse dimensions to the height or length of a light confining device depends on the characteristics of the light source 1, on the characteristics of the reflector means 2, and/or on the type of the unit 3. The inner sides of the ducts are coated with light reflecting material.

The improved convertible light confining device can be used in automatic copying apparatus as well as in many other optical apparatus, such as projectors, viewers or light boxes serving to illuminate differently dimensioned slides, frames or motion picture film or the like. This renders it possible to operate a projector without necessitating a replacement or interchange of condensor lenses.

The base and top planes of the smaller and larger ducts need not be rectangles or squares. Thus, the improved light confining device may have any desired polygonal cross-sectional outline.

Without further analysis, the foregoing will so fully reveal the gist of the present invention that others can, by applying current knowledge, readily adapt it for various applications without omitting features which fairly constitute essential characteristics of the generic and specific aspects of my contribution to the art and, therefore, such adaptations should and are intended to be comprehended within the meaning and range of equivalence of the claims.

What is claimed as new and desired to be protected by Letters Patent is set forth in the appended:

1. In a lamp housing, particularly for use in photographic projection printers, a light confining and guiding device comprising a plurality of walls movable between first positions in which said device constitutes a first light duct in the form of a first hollow truncated pyramid with spaced apart top and base planes and contiguous sides which confine light that enters said first duct by passing across one of said planes and issues from said first duct by passing across the other of said

planes, and at least one second position in which said device constitutes a different second light duct having the form of a second hollow truncated pyramid with spaced apart top and base planes and contiguous sides the area of at least one of said planes of said second pyramid being different in size from the area of the corresponding plane of said first pyramid.

2. A light confining device as defined in claim 1, wherein the length of said first light duct, as considered in the direction of the passage of light therethrough, is identical with the length of said second light duct.

3. A light confining device as defined in claim 1, wherein one of said light ducts is located within the confines of the other of said light ducts.

4. A light confining device as defined in claim 1, wherein said second light duct has a first open end in one of said planes and a second open end in the other of said planes.

5. A light confining device as defined in claim 4, wherein the area of said first end is identical with the area of said one plane and the area of said second end is different from the area of said other plane.

6. A light confining device as defined in claim 1, wherein said walls constitute portions of the sides of said first light duct.

7. A light confining device as defined in claim 6, wherein said walls are pivotable between said first and second positions about axes which are located in the region of said top plane.

8. A light confining device as defined in claim 7, wherein said walls are further movable at right angles to the respective axes in the course of said pivotal movement thereof.

9. A light confining device as defined in claim 7,

wherein each side of said first light duct further comprises corner portions flanking the respective wall in the first position of such wall.

10. A light confining device as defined in claim 9, further comprising a frame which is rigid with said corner portions.

11. A light confining device as defined in claim 9, wherein said walls make with said base plane a first angle in said first positions thereof and a second angle in said second positions thereof, said second angle being at least equal to said first angle.

12. A light confining device as defined in claim 11, wherein said second angle is greater than said first angle and each side of said first light duct further comprises a sill adjacent to said base plane, extending between the respective corner portions and being flush with the respective wall in said first position of the respective wall.

13. A light confining device as defined in claim 1, wherein said walls are rectangular and the cross-sectional area of said second light duct is substantially constant from end to end.

14. A light confining device as defined in claim 1, further comprising means for simultaneously moving said walls between said first and second positions.

15. A light confining device as defined in claim 14, wherein said means for moving comprises means for biasing each of said walls to one of said positions thereof.

16. A light confining device as defined in claim 14, wherein said means for moving comprises followers provided on said walls and means for moving said walls by way of the respective followers.
